(57) **CLAIM**

The ornamental design for a golf ball and golf tee holder, as shown and described.

DESCRIPTION

FIG. 1 is a perspective view of the golf ball and golf tee holder when viewed from the right side, showing my new design;

FIG. 2 is a front elevational view;

FIG. 3 is rear elevational view;

FIG. 4 is a side elevational view when viewed from the right side;

FIG. 5 is a side elevational view when viewed from the left side;

FIG. 6 is a top plan view;

FIG. 7 is a bottom plan view;

FIG. 8 is a perspective view illustrating two golf balls and one tee retained by the device; and,

FIG. 9 is a front elevational view illustrating two golf balls and two tees retained by the device.

The broken line showing is for illustrative purposes only and forms no part of the claimed design.
